UNITED STATES PATENT OFFICE.

ANTON METZEL, OF LONSDALE, MINNESOTA.

SAFETY-STIRRUP.

995,166.

Specification of Letters Patent Patented June 13, 1911.

Application filed September 29, 1910. Serial No. 584,506.

To all whom it may concern:

Be it known that I, ANTON METZEL, a citizen of Austria, residing at Lonsdale, in the county of Rice and State of Minnesota, have invented certain new and useful Improvements in Safety-Stirrups; and I do declare the following to be a full, clear, and exact description of the invention, such as will enable others skilled in the art to which it appertains to make and use the same.

This invention relates to an improved safety stirrup.

The object of the invention is to construct a simple and efficient safety stirrup in which one or both side members will automatically open should a rider fall from his horse, and thereby reliably protect him against being caught in the stirrup and dragged.

With this and other objects in view, the invention consists of certain novel features of construction, combination and arrangement of parts as will be more fully described and particularly pointed out in the appended claims.

In the accompanying drawings, Figure 1 is a perspective view of this improved stirrup, with the members in normal position; Fig. 2 is a longitudinal vertical section thereof; Fig. 3 is a transverse vertical section; Fig. 4 is a vertical section of the casing with the toe piece in place. Fig. 5 is a perspective view of the other casing member; Fig. 6 is a detail perspective view of the free end of one of the foot sections; Fig. 7 is a similar view of the toe piece.

In the embodiment illustrated, the stirrup includes a hanger section 1 and a foot supporting section 2, the two being detachably united by a catch mechanism hereinafter to be described, which mechanism is tripped or released by the movement of a toe piece 3.

The foot support 2 is composed of two substantially L-shaped twin sections 4 and 5, with their short arms hingedly connected at their free ends as shown at 6. The inner faces of the short arms of these L-shaped members are provided with recesses 7 and 8 to receive the opposite ends of an upwardly bowed plate spring 9 which is connected intermediately of its ends to the lower face of a foot lever or plate 10 which plate is pivotally connected intermediate of its ends to the pintle of the hinge connection 6. This spring 9 tends to force the members 4 and 5 into open position and causes them to spring apart when the upper

ends thereof are disengaged from the catch mechanism which locks them together. Two lugs 11 and 12 project laterally from the inner faces of the upper ends of the members 4 and 5 intermediately of the width thereof and are provided with catch receiving apertures as 13, and also with auxiliary apertures as 14 preferably of smaller size, and which are designed to receive locking screws as 15 which secure them against separation from the hanger member. The inner faces of the upper ends of the members 4 and 5 are preferably provided with longitudinally extending ribs 4^a and 4^b and 5^a and 5^b, respectively, which are arranged on opposite sides of the lugs 11 and 12. The ribs 4^a and 5^a are spaced laterally from said lugs a sufficient distance to permit the insertion between said ribs and lugs, of the flanges of the hanger section to be described, when the parts are in operative position. The free ends of these lugs 11 and 12 are preferably beveled to facilitate their insertion within the casing in a manner hereinafter to be described.

The hanger section 1 comprises a plate having a strap loop 16 at its upper end and with its lower end extended to form a central partition 17 in the casing 19, which carries the catch mechanism. This partition 17 is provided with a plurality of transversely spaced apertures as 20 through which catch pins as 21 and 22 carried by the toe piece 3 are adapted to operate. At one side of this partition 17 is formed a chamber 23 open at its opposite ends to receive lugs 11 and 12 of the foot supporting member. When the beveled ends of these lugs are forced into said casing, they cause the pins 21 and 22 to spring backwardly until the apertures 13 in said lugs register with said pins. When in this position the pins spring forwardly through said apertures and lock the lugs 11 and 12 securely within the casing. Arranged on the other side of the partition 17 is a chamber 24 in which extends the free end of an upright plate 27 secured to the toe-piece 3, said toe-piece being preferably made arc-shaped, as shown. Pins 21 and 22 project at right angles from one face of laterally extending arms 25 and 26 fixed to the upper or free end of said plate. A stud 28 projects laterally from the outer face of the plate 27 through an aperture formed in the outer wall of the chamber 24, and a coiled spring 29 is arranged on this

stud between the inner faces of the outer wall of said chamber 24 and outer face of said plate 27, and exerts its tension to force the pins 21 and 22 normally through the partition 17 into locking position within the chamber 23. This stud 28 is preferably connected with said plate by being screwed therein and is provided at its outer end with a kerf for inserting and removing it, 10 as shown in Fig. 1. The upper end of the plate 27 is preferably provided with laterally projecting outwardly extending lugs 30, preferably formed by bending the corners of said plate to form stops for limiting the outward movement of the stud 28. The members of the casing 19 are detachably connected together and to the partition 17 by means of screws or any other suitable fastening devices. The chamber 24 is provided at its opposite ends with flanges as 24^a which lie in close contact with the adjacent face of the partition 17 near its side edges, the edges of said plate and said flanges extending into the space between the ribs 4^a and 5^a and the lugs 11 and 12 of the members 4 and 5. Right angular flanges as 23^a are formed on the end walls of the chamber 23 below and above the openings therein, and these flanges 23^a abut against the ribs 4^a and 5^a of the members 4 and 5 when the parts are in operative position. The outer wall of the chamber 23 is provided with apertures as 31 which are designed to register with similar apertures as 14 in the lugs 11 and 12 to receive the screws as 15, which may be used for locking the side members of the stirrup against automatic separation. 15 If desired, one side member of the foot supporting section may be locked against opening by one of the screws 15, or both may be locked if so desired, or the screws may be dispensed with and both side members caused to spring automatically open 20 when the toe piece 3 is moved laterally by the engagement of the rider's foot therewith. It will be obvious that the plate 27, which is secured to the toe piece 3 and extends upwardly through a slit in the bottom of the chamber 24, being provided with the laterally extending stud 28 which operates through and is guided by an aperture in the outer wall of said chamber 24, will permit said toe piece to be moved laterally in 25 one direction by the engagement of the rider's foot therewith and in the opposite direction by the coiled spring 29. The lateral movement of the toe piece 3 produced by the engagement of the toe of the rider causes the stud 28 to be moved outwardly 30 against the tension of the spring 29, which forces the pins 21 and 22 out of engagement with the apertured lugs 11 and 12 of the sections 4 and 5 of the foot supporting member whereby said sections are forced apart

by the action of the spring 9 and the foot support is thus quickly separated from the hanger and all danger of the rider being dragged is thereby prevented.

From the foregoing description taken in connection with the accompanying drawings, the construction and operation of the invention will be readily understood without requiring a more extended explanation.

Various changes in the form, proportion and the minor details of construction may be resorted to without departing from the principle or sacrificing any of the advantages of the invention, as defined in the appended claims.

80 I claim as my invention:

1. A safety stirrup comprising a foot supporting member composed of hingedly connected twin sections provided at their free ends with inwardly extending lateral apertured lugs, a hanger member having a lug receiving chamber and transversely movable spring actuated locking pins operable to normally engage the apertures in said lugs, means operable by the foot of the rider for disengaging said pins from said lugs and means for forcing the lugs on said sections out of said chamber when disengaged from said pins.

2. A safety stirrup comprising a hanger member, two L-shaped members having the free ends of their short arms hingedly connected and their upper faces recessed, a plate pivotally mounted over said hinge connection, a plate spring secured intermediate of its ends to the lower face of said plate with its ends engaged in said recesses, means for detachably connecting the free ends of said L-shaped members to said hanger, and a trip member operable to release said connecting means.

3. A safety stirrup comprising a foot supporting member having laterally extending apertured lugs on the inner faces of its free ends, a hanger member having a casing with a central partition therein, a laterally movable toe piece having a plate extending into one chamber of said casing, said plate being provided with laterally spaced pins on one face slidable through apertures in said partition, a laterally extending stud on the other face of said plate mounted to slide in an aperture in the outer wall of said casing chamber, and a coiled spring arranged on said stud between said plate and said casing wall, said pins being operable to detachably engage said apertured lugs.

4. A safety stirrup comprising a foot supporting member composed of hingedly connected twin sections provided at their free ends with inwardly extending apertured lugs, a hanger member having a lug receiving casing, a laterally movable toe-piece having a plate extending into said casing, said plate being provided with means for

- detachably engaging said lugs, a laterally extending stud secured at one end to said plate and with its other end mounted to slide in an aperture in the outer wall of said casing, and a spring arranged to hold said stud normally within said casing.
5. A safety stirrup comprising a foot supporting member composed of hingedly connected twin sections provided at their free ends with inwardly extending apertured lugs, a hanger member having a lug receiving casing, a laterally movable toe-piece having a plate extending into said casing, said plate being provided with means for detachably engaging said lugs, a laterally extending stud secured at one end to said plate and mounted to slide in an aperture in the outer wall of said casing, and means for limiting the outward movement of said stud.
- 10 6. A safety stirrup comprising a foot supporting member composed of hingedly connected twin sections provided at their free ends with inwardly extending apertured lugs, a hanger member having a lug receiving casing, a laterally movable toe-piece having a plate extending into said casing, said plate being provided with means for detachably engaging said lugs, a laterally extending stud secured at one end to said plate and 15 mounted to slide in an aperture in the outer wall of said casing, and means carried by said plate for limiting the outward movement of said stud.
- 15 7. A safety stirrup comprising a foot supporting member composed of hingedly connected twin sections provided at their free ends with inwardly extending apertured lugs, a hanger member having a lug receiving casing with a vertical partition therein provided with a plurality of transversely spaced apertures arranged to register with the apertures in said lugs, a laterally movable toe-piece having an upright plate extending into said casing at one side of said partition, arms extending laterally from 20 opposite edges of said plate in the same plane, a pin extending at right angles from one face of each of said arms in position to normally engage the apertures in said partition and lugs, and means for holding said pins normally in engagement with said apertures and operable by the toe-piece to release them.
- 25 In testimony whereof I have hereunto set my hand in presence of two subscribing witnesses.
- 30
